[57] ABSTRACT

A method and a device for introducing or removing an electrical signal through rapid switching of an analog switch between the on and off conditions with the switch remaining in one condition longer initially, and then progressively less in the one condition and longer in the other until the transfer has been completed. The magnitude of a repetitive waveform is compared with the magnitude of a ramp waveform to generate the control signal which determines the interval that the switch remains in a given condition. By controlling the on and off condition of a second switch in opposition to the first switch and by combining the outputs of the switches, a smooth transition between two control signals is achieved. The method and the device are applied to an elevator speed control system wherein transition is provided between several signal sources.

SWITCHING TECHNIQUES AND DEVICES

BACKGROUND OF THE INVENTION

1. Field of the Invention

This invention relates to switching devices and techniques and more particularly to such devices and techniques for use in switching control signals wherein the application of a signal or the switching between signal sources must be smooth.

2. Prior Art

With conventional switching techniques wherein a switch is operated from the closed to the open position or vice versa in one step, the signal being switched is introduced or removed rapidly. The transients introduced by such switching when utilized in control circuits can induce undesirable response in the system being controlled. As a result, it has become the practice, in some instances, to introduce such signals through filters. However, this technique has the disadvantage that since the filter remains in the circuit, it can dampen the desired response of the system to variations in the control signal once it has been switched on. It is also possible to introduce such a signal at a controlled rate through the use of a potentiometer; however, this has the disadvantage of requiring a mechanism for driving the wiper arm with the accompanying problems of mechanical wear.

Smooth switching is also a problem in systems wherein a transfer is made from one signal source to another, as from a coarse control signal to a fine control signal or vice versa. Such problems arise in the speed control systems for elevators. For instance, very often the speed control signal for acceleration and constant speed is generated as a function of time, while the speed control signal for the deceleration phase is controlled as a function of the distance remaining to the point at which the car is to stop. In some instances, a third signal generator is utilized to generate a very accurate speed control signal over the last few inches of travel to assure accurate landings. The problem of providing smooth transition from one signal source to another is particularly acute in the elevator field since passengers are free standing on a moving platform. One approach to this problem has been to attempt to match the magnitudes of the control signals so that they will be approximately equal at the point when the switchover should occur. However, when the control signal is used for a speed control, not only the magnitudes of the signal must be approximately equal, but the slope, or rate of change of the control signals, must also match or approximate each other at the time of switchover or undesirable transient response will occur.

SUMMARY OF THE INVENTION

According to the invention, an analog switch is switched between its on and off conditions rapidly and repetitively with said switch initially remaining in one condition longer than the other and then progressively less in the one condition and longer in the other until the switch remains in the other condition substantially continuously. The condition of the switch is controlled by the output of a comparator which has one or another condition depending upon whether the instantaneous value of a ramp function is more than or less than the instantaneous value of a repetitive function, preferably a sawtooth function. The minimum value of the ramp function is made less than the minimum value of the sawtooth function while the maximum value of the ramp function is made more than the sawtooth function so that the output of the comparator changes, and therefore the condition of the switch changes, only when the ramp function is transferring between its peak values.

The transition time of the ramp function determines the transfer time from the full on to the full off condition of the switch and therefore establishes the rate at which the signal is applied or removed. Since the components which control this transfer time are in the control circuit for the switch and not in the circuit being switched, they do not affect the response of the control system to the transients in the control signal being

switched as would a filter. Consequently, the transfer time can be made reasonably slow without affecting the dynamic response of the system to the control signal once it is switched on.

5 The frequency of the sawtooth function determines the rate at which the switch is operated between the off and on conditions. If this rate is made rapid with respect to the response time of the system being controlled by the switched signal, the effect will be a smooth application or removal of the signal with the rate determined by the transition time of the ramp.

10 By connecting a second switch so that it is switched from the off to the on condition in opposition to the first switch in response to the output of the comparator, and by combining the outputs of the two switches in a summing circuit, the invention can be used for switching smoothly from one control signal to another. Again the transfer time will be determined by the transition time of the time ramp function and the rate of repetitive switching will be determined by the frequency of the sawtooth waveform. The second switch is operated in opposition to the first switch by interposing a conventional NOT logic circuit between the comparator and the second switch. With this configuration, one switch will be on 100 percent of the time initially while the other one will be off 100 percent of the time. As the transition occurs, the relative percentage of 15 contribution of the two signals will change progressively until the one switch will be off 100 percent of the time while the other switch will be on 100 percent of the time.

20 In the preferred embodiment of the invention, the ramp function is controlled as a function of time; however, the value of this waveform could be controlled as a function of another variable such as the position of the body being controlled.

25 The invention can also be applied to systems wherein a control signal is selected from more than among two signal sources. As applied to an elevator system wherein a speed control signal is selected from among three signals, only one sawtooth generator is required while ramp function generators for each pair of signal sources between which a transfer is desired are required. Separate comparators are required for comparing the value of the sawtooth waveform with the waveform of each of the ramp function generators. Gate circuits operated by a supervisory control serve to insure that 30 operation of a switch controlling a signal source common to two transfers is controlled by the output of the proper comparator.

BRIEF DESCRIPTION OF THE DRAWINGS

FIG. 1 is a block diagram of a basic embodiment of the invention;

FIG. 2 is a block diagram of another embodiment of the invention adapted for use in switching between two signal sources;

FIG. 3 is a block diagram of yet another embodiment of the invention adapted for use in an elevator speed control system;

FIGS. 4A through 4E illustrate waveforms appearing at various points in the circuit of FIGS. 1 through 3.

DESCRIPTION OF THE PREFERRED EMBODIMENTS

60 FIG. 1 illustrates the invention as employed in a simple switching operation to control the circuit between the terminals A and B. The device is composed of an analog switch 1 interposed in the circuit between these terminals. An analog switch is a conventional type of a two condition switch which opens the circuit between terminals A and B in one condition and provides a short circuit so that the signal appearing at the terminal A appears at the terminal B when the switch is in the closed condition. Although the switch could be of the electromechanical solenoid type, preferably the switch is a solid state switching device due to the rapid repetitive switching desired.

65 Solid state switches which are responsive to a digital control signal applied to a control input 2 are well known. An exemplary solid state switch is shown in FIG. 1 within the dashed

75

line. Base electrodes B_1 and B_2 of a field effect transistor Q_1 are connected between the terminals A and B. A resistor R_1 is connected between B_1 and the gate electrode, G, of Q_1 . The gate electrode G is also connected to the collector of an NPN-transistor Q_2 . The emitter of Q_2 is energized by a -15 v. DC source while the base of Q_2 is connected to a -12 v. DC source through resistor R_2 . The control input 2 is connected directly to the base of Q_2 .

With no signal applied to the control input 2 of the switch 1, the transistor Q_2 will conduct. The current thus drawn through resistor R_1 will lower the voltage on the gate G of transistor Q_1 , to hold Q_1 cut off and the switch 1 will therefore be in the open condition. When a signal which lowers the potential of the base of Q_2 below -15 v. DC is applied to the control input 2, Q_2 is cut off and the potential on the gate G of transistor Q_1 will rise so that Q_1 will be turned on. With Q_1 conducting the switch 1 is in the closed condition. It will be appreciated that if no control signal is applied to the control input 2, switch 1 will be biased to the open condition.

The control signal for the analog switch is generated by a comparator 3 which has one output when the instantaneous value of a signal applied to an input 4 exceeds the instantaneous value of signal applied in input 5 and a second output when the signal applied at the input 5 exceeds the value of the signal applied at the input 4. Comparators displaying such characteristics, and having as one output a zero voltage signal and having as a second output a signal of a fixed magnitude are well known. Signals to be compared by the comparator 3 are supplied by a first function generator 7 which generates a repetitive waveform, preferably a sawtooth waveform, and a second function generator 8 which preferably generates a ramp function. The sawtooth function generator 7 can operate continuously while the ramp function generator 8 maintains an output of one peak value or the other until triggered by a transition signal, whereupon the ramp function transitions to the opposite peak value. Function generators of these general characteristics are also well known.

Reference to FIG. 4 will aid in understanding the operation of the device of FIG. 1. Assuming that initially the ramp function R is at its minimum value which is less than the minimum value of the sawtooth function S (see FIG. 4A), the signal appearing at input 4 of the comparator will exceed the signal applied to the input 5 so that the output of the comparator will remain constant. If it is assumed that this output when applied to the control input 2 of the analog switch 1 is such as to maintain the switch in the open circuit state, the condition of the switch would be as shown in FIG. 4B. Suppose now that a transition signal is applied to the ramp generator 8 to cause the generation of a ramp function. As the ramp function R begins to rise in value at t_1 , the output of the comparator, and therefore the condition of the analog switch, remains constant since the instantaneous value of the sawtooth waveform S continues to exceed the value of the ramp function. However, at the completion of the second cycle of the sawtooth waveform shown in FIG. 4A, the instantaneous value of the ramp function R exceeds that of the sawtooth waveform. Since the value of the signal applied to the input 5 of the comparator now exceeds the value of the signal applied to the input 4, the output of the comparator 3 switches thereby causing the operation of the analog switch 1 to the closed condition. Since the value of the sawtooth waveform soon exceeds the value of the ramp function again, the output of the comparator, and therefore the condition of the analog switch, quickly switch back to their original states. It can be seen therefore, that any signal applied to the terminal A of the device of FIG. 1 appears at the terminal B for only a very short interval. It can be appreciated from FIGS. 4A and 4B, however, that the value of the ramp function exceeds that of the sawtooth function for a longer interval after the completion of the third cycle of the sawtooth waveform. Consequently, the analog switch 1 remains closed for a longer interval on this cycle. It is clear from FIGS. 4A and 4B that the ramp function R remains larger than the sawtooth function S for longer intervals on successive cycles of

the sawtooth function so that the switch remains in a closed position for successively longer intervals until after the seventh cycle of the sawtooth function the switch remains permanently in the closed condition.

5 The relationship between the instantaneous value of the sawtooth function and the ramp function in FIGS. 4A and 4B was selected for the sake of clarity. In actuality the slope of the ramp function R would be much less so that hundreds of incremental switching operations would occur as the ramp function transitions from its minimum to its maximum value. For instance, it has been found that when the device is applied to a speed control system for an elevator as described in detail below, satisfactory switching is achieved by utilizing a ramp function which transitions from one peak to the other in three 10 tenths of a second and a sawtooth function which has a period of 1 millisecond. With these parameters, nearly 300 switching operations will occur as the analog switch 1 is progressively switched from being predominantly in the open circuit condition to being predominantly in the closed circuit condition. 15 The exact figure will be somewhat less than this as determined by the amount by which the peak values of the ramp function exceed the peak values of the sawtooth function thereby eliminating some of the switching operations while the ramp function is near its peak values. It can be appreciated, therefore, that the signal appearing at terminal B will have a 1 kilocycle component during the switching operation. In many applications the dynamics of the system will be such that this one kilocycle transient will be automatically damped. However, 20 if desired, a low pass filter 9 can be inserted between the analog switch and the terminal B to eliminate this component. 25

The transition time of the ramp function however, is the operative factor which determines the rate at which the analog switch is operated from its predominantly closed to its 30 predominantly open condition. Referring to FIG. 4D, if a continuous signal shown by the dotted line a is present at the input terminal A, the signal appearing at the terminal B is represented by the solid line b. Again this is an idealized representation which illustrates the theoretical signal which 35 would appear at the terminal B. In reality, the signal at terminal B will approach this signal as the frequency of the sawtooth waveform is increased with respect to the transition time of the ramp function. It can be seen however, that the signal at terminal B will be zero until the ramp function begins to exceed the value of the sawtooth function during part of the 40 cycle of the sawtooth function. It can be appreciated then that the signal applied to the terminal A appears at the terminal B smoothly over a period of time determined by the transition time of the ramp function. As was mentioned previously, this 45 transition time in one application has been set at three tenths of a second. It will be noted however, that once the switching has been completed there is no restriction in the circuit 50 between the terminals A and B to inhibit the response of a component connected to the terminal B to transient signals applied to the terminal A.

In other words, through the utilization of this invention, the signal appearing at A can be applied to the system connected to the terminal B at a rate which is compatible with the dynamic characteristics of the load but yet it does not interpose a reduction in the response time of the system. This should be contrasted with the prior art procedure of interposing a filter in series with a switching circuit to dampen the response of the system to the switching operation. If the filter is to dampen the response of the system to the transient caused by the switching operation it will also dampen the response of the system to transients in the control signal applied to the terminal A. According to this invention however, the components which control the switching operation are in 60 control circuit for the analog switch and not in the load circuit, therefore once the switching operation is completed they do not inhibit the response of the load to transients in the signal applied to the terminal A. It should be remembered that the low pass filter 9 which may be interposed in the load circuit will pass all frequencies occurring in the normal transients 65 70 75

of the control signal applied to the terminal A. It merely eliminates the high frequency transients caused by the switching operation itself and, as was mentioned, if the cut off frequency of the system is low enough, this filter is not necessary.

It is apparent that the signal applied to the terminal A can be removed from terminal B through the reverse switching process by a transition of the ramp waveform back to its original value. This could be accomplished by the removal of the transition signal from the ramp function generator 8. During this transition, analog switch 1 would initially predominantly remain in the closed condition and then progressively less in the closed condition and more in the open condition during successive cycles of the sawtooth function until the value of the ramp function dropped below the minimum value of the sawtooth function so that the switch would remain in the open circuit condition. It can be appreciated that although a sawtooth function and a ramp function were selected to provide a linear transition in the switching operation, other repetitive waveforms can be substituted for the sawtooth function and another transition function could be substituted for the ramp function.

FIG. 2 illustrates the application of the invention to a dual switching operation for switching between two signal sources. The two signal sources are connected to the terminals A and A'. Analog switch #1 is interposed between terminal A and the output terminal B while the analog switch #2 is interposed between the terminal A' and the output terminal B. The analog switch #1 is controlled by the signal applied to its control terminal 2 in a manner similar to that described for the control of the analog switch in the device of FIG. 1. In other words, analog switch #1 is controlled by the output of the comparator 3 which generates a digital signal having a value of either zero or one depending upon whether the value of a sawtooth waveform applied to input terminal 4 of the comparator is larger than, or less than, the value of a ramp function applied to the input terminal 5 of the comparator.

For illustrative purposes, it will be assumed that the analog switch #1 of FIG. 2 will respond to the relative values of the ramp function and the sawtooth function as did the analog switch of FIG. 1 so that its condition is represented by the FIGS. 4A and 4B. The additional analog switch #2 is also operated between its open and closed condition by a control signal applied to its control terminal 2'. The control terminal 2' is connected to the output of the comparator 3 through a conventional NOT-logic circuit 10. The conventional NOT circuit reverses the digital signal applied to its input. For instance, if a ONE is applied to the input of the NOT element 10 a ZERO output is produced and vice versa. Therefore, the control signal applied to the control input 2' of analog switch #2 will at all times be opposite to the control signal applied to the control terminal 2 of the analog switch #1. It is clear then that when the analog switch #1 is in closed condition analog switch #2, which is identical to the analog switch #1, will be in the open condition and vice versa.

Since it was assumed that the condition of analog switch #1 with respect to the relative values of the ramp function and the sawtooth function would be illustrated by FIG. 4B, the operation of the analog switch #2 with respect to the ramp function and sawtooth function is illustrated by FIG. 4C. It will be noted that for the assumed conditions analog switch #2 is initially predominantly in the closed condition and progressively remains a shorter interval in the closed condition and longer in the open condition through successive cycles of the sawtooth function. It can be appreciated then that only one switch at a time is in the closed condition so that either the signal applied to the terminal A or A' alone is passed to the terminal B. A summing circuit 11 connected to the two analog switches supplies the combined signal to the terminal B. The summing circuit can be a conventional operational amplifier which may also be modified to act as a low pass filter if necessary. Alternatively, the summing circuit could be replaced by a voltage follower circuit.

FIG. 4E illustrates the operation of the circuit of FIG. 2. It will be assumed that the signal #1 shown as a dashed line is applied to terminal A and that signal #2 illustrated as a dotted line is applied to the terminal A'. The solid line 5 represents the resultant signal appearing at the terminal B assuming that the summing circuit 11 does not operate as a low pass filter. The dash dot line curving between the signal #2 and signal #1 represents the effective value of the signal appearing at the terminal B assuming that the summing circuit 11 also acts as a low pass filter. Under the assumed conditions, when the ramp function R of FIG. 4A is smaller in value than the sawtooth function S so that the analog switch #1 is opened and the analog switch #2 is closed, the signal #2 appears at the output terminal B. At the beginning of the third illustrated cycle of the sawtooth waveform when the ramp function momentarily exceeds the value of the sawtooth function, analog switch #1 will close while the analog switch #2 will open momentarily thereby causing the signal which appears at the output terminal B to drop to the instantaneous value of the signal #1. With successive cycles of the sawtooth function, it can be seen that the signal #1 progressively appears longer at the output terminal B than the signal #2 as the switch #1 progressively remains longer in the closed condition while the switch #2 remains progressively longer in the open condition. It can be seen that after the seventh illustrated cycle of the sawtooth waveform, the switch #1 remains closed while switch #2 remains open so that signal #1 applied to the A-terminal of the device of FIG. 2 appears at the output terminal B continuously. Obviously the output of the device can be switched back to signal #2 by causing the ramp function to transition from its maximum value back to its minimum value. The filtered value of the signal appearing at the output terminal B of course will follow the dash dot line which represents a weighted average of the signals during the transition period.

FIG. 3 illustrates the application of the invention to an elevator speed control system. In this system, elevator car 20 is suspended from a cable 21 which passes over a sheave 22 and is connected to a counterweight 23. The car 20 is caused to travel up and down serving a number of landings by a motor 24 which rotates the sheave 22 through a shaft 25. The shaft 25 also drives a floor selector 26. The floor selector is a device well known in the elevator art which follows the position of the car relative to the landings and cooperates with a supervisory control 27 to initiate the stopping of the elevator car as it approaches a floor at which service is desired. In many elevator systems the floor selector operates as a pattern generator which develops a speed control signal as a function of the distance remaining to a floor at which the car is to stop.

It has been found that good results can be achieved by controlling the speed of a car during acceleration as a function of time to provide comfortable and smooth acceleration for the passengers. Therefore, a time ramp generator 28, which is triggered by the supervisory control system when the car is to start, can be utilized to generate a control signal for controlling the speed of the car during acceleration. It has become common practice to utilize this ramp generator also to control the speed of the car during the constant speed phase. However, as the car approaches a landing at which it is to stop, accurate landings with smooth deceleration and no overshoot can be achieved by controlling the speed of the car as a function of the distance remaining to be traveled. This signal is most often generated by pattern generator connected to the floor selector. Due to the technical restrictions of size and cost, this signal produced by the pattern generator is a rough signal which controls the car very well during the initial stages of deceleration. However, to assure precise landing without overshoot, it has become widespread to utilize a third signal generator to control the speed of the car precisely during the last critical inches of travel. A device for producing this fine signal is illustrated in U.S. Pat. No. 2,874,806. According to this system an electromagnetic transducer 29 connected to the elevator car is activated as the car approaches a landing at

which it is to stop. Diamond shaped magnetic plates P, located adjacent each landing, vary the coupling between the poles of the transducer. The inductor plates are so located with respect to the landings that a null signal is produced by the transducer when the car is exactly level with the landing.

The speed of the car then is controlled by a signal developed either by a time ramp generator, a distance dependent pattern generator or a landing transducer depending upon the phase of the trip. The application of the selected signal to the motor control circuits is governed by three analog switches similar to those discussed in connection with FIGS. 1 and 2. A time ramp generator which is controlled by a supervisory control system supplies a control signal during acceleration and at constant speed through the analog switch #1. The pattern generator which supplies the signal to the motor control circuit during the deceleration phase is controlled by the analog switch #2. The landing transducer which supplies a control signal during the landing phase is rendered effective by analog switch #3. The output of the terminals of the three switches are connected to the summing and filter circuits 11 similar to that discussed in connection with FIG. 2 which in turn supplies the resultant control signal to the motor and control circuits 24.

The switching of analog switches #1 and 2 is controlled by a circuit similar to that shown in FIG. 2. The instantaneous magnitudes of a sawtooth waveform generated by function generator 7 and of a ramp function generated by function generator 8 determine the digital output of a comparator 3. As in the circuit of FIG. 2, the output of the comparator 3 is reversed by a NOT-circuit 10 before being applied to the control input of analog switch #2. The transition of the ramp function is controlled by a transition signal which is generated by the supervisory control 27. In these respects this portion of the circuit of FIG. 3 is identical to that of FIG. 2.

A second comparator 3' compares the instantaneous value of the sawtooth waveform 7 and a ramp function generated by an additional function generator 8' to also control the switching of analog switch #2 in addition to analog switch #3. A NOT-circuit 10' interposed between the comparator and analog switch #3, assures that opposing control signals will be applied to analog switch #2 and analog switch #3 by the comparator 3'. The function generator 8' is also controlled by a transition signal generated by the supervisory control 27.

In the circuits of FIG. 3, AND-gates 30 and 32 are interposed between comparators 3 and 3' and analog switches #1 and #2 respectively. Similarly AND-gates 31 and 33 are interposed between NOT-elements 10 and 10' and analog switches #2 and #3. All of these AND gates have two inputs and a single output. These gates are the conventional AND logic gates which have a ONE output only when a signal is applied to both inputs. The second input to gates 30 and 31 is the signal LAND generated by the supervisory control system 27. The second input to AND-gates 32 and 33 is the signal LAND generated by the supervisory control system. Signals LAND and LAND are complementary signals in that when one of these signals is equal to ONE, the other one is equal to ZERO. It can be appreciated therefore that the output of only one AND circuit at a time can be equal to ONE. For instance, if the signal LAND is equal to ONE the signal LAND will be equal to ZERO and therefore the output of AND-gates 32 and 33 cannot be equal to ONE regardless of the value of the other input. Since the second input to the AND-gate 31 is the reverse or the complement of the second signal applied to the AND-gate 30, only one of these AND gates at a time will have both inputs equal to one. The signal LAND will be equal to ONE only during the landing phase. At all other times, the signal LAND will be equal to ONE.

A typical trip of an elevator would help in understanding the operation of the system shown in FIG. 3. When the supervisory system indicates that the car should be started the signal LAND will be equal to ONE and the signal LAND will be equal to ZERO. Under these conditions the output of AND-circuits 32 and 33 will be clamped at ZERO. Since it was as-

sumed initially that each analog switch would be operated to the open condition as long as a ZERO signal was applied to the control input, the analog switch #3 will remain in the open circuit condition. The analog switch #2, however, may be controlled by the output of the AND-gate 31 even though the output of the AND-gate 32 is equal to ZERO. Let it be assumed further that the time ramp function produced by the function generator 8 is at its minimum value so that the value of the sawtooth function 7 exceeds the value of the ramp function. Therefore, the output of comparator 3 will be equal to ONE. Since the signal LAND is also equal to ONE, the signal supplied to the control input of analog switch #1 by the AND-gate 30 will be equal to ONE to operate the analog switch #1 to the closed position. Since a ZERO will be supplied to the AND-gate 31 by the NOT-element 10, a ZERO signal will be supplied to the control input of analog switch #2 by AND-gate 31. Therefore, with a triggering of the time ramp generator 28 by the supervisory control, the control signal generated by this element will pass through the closed analog switch #1 and the summing circuit 11 to the motor and its control 24.

Energization of the motor in turn will cause the car 20 to begin to accelerate. Movement of the car will cause the floor selector to move in synchronism with it thereby following the position of the car. Movement of a car will also cause operation of the pattern generator which generates a speed control signal as a function of distance required for the car to come to a stop, however, this signal will not be applied to the motor control circuit since the analog switch #2 is held in the open condition.

As the car approaches a floor at which the supervisory control system indicates that the car is to stop, a transition signal will be supplied to the ramp function generator 8. As the value of the ramp function increases, the output of the comparator 3 will reverse during those intervals when the value of the ramp function exceeds the instantaneous value of the sawtooth function. When the output of the comparator is equal to ZERO, analog switch #1 will be closed while the analog switch #2 will be open due to the operation of the NOT-circuit 10. As described above, as the ramp function continues to build in value, the analog switch #1 will progressively remain longer in the closed condition as the analog switch #2 remains progressively longer in the open condition until full transfer is achieved and the analog switch #1 will remain closed while the analog switch #2 will remain open to apply the distance dependent signal generated by the pattern generator to the motor control circuit through the summing circuit 11.

As the car approaches within a few feet of the landing, the supervisory system will cause the LAND signal to go to ZERO thereby causing the LAND signal to go to ONE. This will transfer control of the switching of the analog switches to the output of the comparator 3' since, with the signal LAND equal to ZERO, the outputs of AND-elements 30 and 31 are clamped at ZERO. It will be assumed that at this point, with the output of the function generator 8' at its minimum value, the output of comparator 3' will be equal to one to maintain the analog switch #2 in the closed condition so that the control signal generated by the pattern generator will be continuously applied to the motor control circuit 24. At this time, the supervisory control system will supply a transition signal to the function generator 8' to initiate a transfer from the pattern generator to the landing transducer. During those initial periods when the instantaneous value of the function generator exceeds that of the sawtooth function, the output of the comparator 3' will go to ZERO thereby switching analog switch #2 to the open condition and analog switch #3 to the closed condition. In a manner which should be evident at this point, the signal generated by the pattern generator will be smoothly replaced by the signal generated by the landing transducer.

It can be seen from the above description that the gates 31 and 33 are essential for selecting which comparator will con-

trol the operation of analog switch #2. Considering that the initial states of the function generators 8 and 8' are properly selected, the LAND inputs to the AND-gates 30 and 31 are not essential but are useful in providing backup protection should a malfunction occur.

It is evident from FIG. 3 that additional switches can be controlled by adding additional sets of comparators and ramp function generators. The same or a separate sawtooth function generator 7 can be utilized for each stage. Of course the proper gating signals for the AND gates must be supplied to insure the selective control of the individual analog switches.

It is to be understood that the invention is not to be restricted to the embodiments specifically disclosed since it is evident that any variations fully within the scope of the invention could be made.

We claim as our invention:

1. A switching device comprising a switch having an input terminal and an output terminal, said switch being operative between a first condition wherein a circuit is completed between the input terminal and the output terminal and a second condition wherein no circuit is completed between the terminals, and control means for operating said switch between said first and second conditions including means operative to rapidly and repetitively operate the switch between said first and second conditions with said switch initially remaining in one condition longer than the other and then progressively less in the one condition and longer in the other condition until the switch remains in the other condition substantially continuously.

2. The device of claim 1 including a summing circuit operative to produce an output signal which is a combination of the signals applied to the summing circuit, a first signal source connected to said summing circuit, a second signal source connected to the input of said switch and means connecting the output of said switch to said summing circuit whereby the signal generated by the second signal source can gradually be added to or removed from the signal appearing at the output of the summing circuit through the operation of said control means to operate said switch from being predominantly in one condition to being predominantly in the other condition.

3. The device of claim 1 wherein said control means comprises a first function generator operative to generate a repetitive signal, a second function generator operative to generate a second signal having a time constant which exceeds the period of oscillation of said first signal, and a comparator for comparing the instantaneous values of the signals generated by said function generators and having a first output when the instantaneous value of a first one of said signals exceeds the instantaneous value of the other and having a second output when the instantaneous value of the other signal exceeds that of said one signal, said switch being operative to one condition in response to the first output of said comparator and operative to said other condition in response to said second output.

4. The device of claim 3 wherein a signal generated by said first function generator is substantially a sawtooth signal wherein the signals generated by the second function generator is substantially a ramp function, the minimum value of said ramp function being less than the minimum value of said sawtooth function while the maximum value of the ramp function exceeds that of said sawtooth function whereby the output of the comparator and therefore the condition of the switch will remain constant except while said ramp function generator is transitioning between its peak values.

5. The device of claim 1 including a second switch which is operative between a first condition wherein a circuit is completed between an input terminal and an output terminal and a second condition wherein no circuit is completed between the terminals, and wherein the control means includes coupling means operative to operate said second switch between said first and second conditions in opposition to the operation of said first switch between said first and second conditions whereby as said first switch is operated from being predominantly in said one condition to being predominantly in

the other condition, said second switch is operated from being predominantly in said other condition to being predominantly in said one condition.

6. The device of claim 5 wherein said control means comprises a first function generator operative to generate the repetitive waveform, a second function generator operative to generate a second waveform having a time constant which exceeds the period of oscillation of said first waveform, and a comparator for comparing the instantaneous values of the first and second waveforms and having a first output when the instantaneous value of one waveform exceeds that of said other waveform and having a second output when the instantaneous value of said other waveform exceeds that of said one waveform, said first switch being operative to said first condition in response to one output of said comparator and being operative to said second condition in response to the other output of said comparator while said coupling means operates said second switch to said second condition in response to said one output of said comparator and operates it to said first condition in response to the other output of said comparator.

7. The device of claim 6 adapted for use in a control system wherein the second waveform is essentially a ramp function with a minimum value which is less than the minimum value of said repetitive waveform and a maximum value which exceeds the maximum value of the repetitive waveform and including a first control signal source connected to the input terminal of said first switch, a second control signal source connected to the input terminal of said second switch, and a summing circuit connected to the outputs of said switches whereby the control signal appearing at the output of the summing circuit is one control signal or the other while the ramp function is at its maximum or minimum value and is progressively switched from one control signal to the other as the ramp function transitions from one peak value to the other.

8. The combination of claim 7 including a third switch operative between a first condition wherein a circuit is completed between an input terminal and an output terminal and a second condition wherein no circuit is completed between the terminals, a third control signal source connected to the input of said third switch the output of said third switch being connected to the summing circuit, an additional second function generator operative to generate a waveform having a time constant which exceeds the period of oscillation of said first waveform, an additional comparator connected to the first function generator and the additional second function generator and having a first output when the value of one of these waveforms exceeds that of the other and having a second output when the value of the other waveform exceeds that of said one waveform, the condition of said second and third switches being responsive to the output of said additional comparator, additional coupling means for operating said second and third switches in opposition to each other in response to the output of said additional comparator and actuating means operative to selectively actuate a selected second function generator to initiate a switching from one control signal to another.

9. The combination of claim 8 including gates between the comparators and the respective switches to which they are connected, said actuating means also including means for actuating said gates to control the response of said switches to the outputs of said comparators whereby the response of the individual switches is controlled by a selected comparator.

10. The combination of claim 7 adapted for use in an elevator system comprising a structure giving it to at least two landings, a car mounted for movement relative to the structure to serve the landings, and regulating means for regulating the speed of the car in response to the speed control signal appearing at the output of the summing circuit, said first control signal source generating a course speed control signal, while said second control signal source generates a fine speed control signal, and actuating means responsive to the approach of a car to a landing at which it is to stop to actuate said second function generator to initiate switching from said course speed control signal to said fine speed control signal.

11. The combination of claim 10 wherein the coarse speed control signal is a time dependent signal and the fine control signal is a function of the distance to the floor at which the car is to stop.

12. A method of operating a first switch having an open circuit condition and a closed circuit condition from being predominately in a first one of said conditions to being predominately in a second one of said conditions, comprising the steps of: generating a repetitive function, generating a ramp function when it is desired to operate said first switch, said ramp function having minimum and maximum values which are less than, and greater than, the respective minimum and maximum values of the repetitive function, comparing the repetitive and ramp functions, operating said first switch repeatedly between said first condition and said second condition in response to the instantaneous value of the repetitive function exceeding and dropping below the instantaneous value of the ramp function, with the interval that said switch remains in each condition being varied according to the transition time of the ramp function, so that initially it remains longer in said first condition and then progressively less in said first condition and longer in said second condition until it remains predominately in said second condition.

13. The method of claim 12 adapted for switching between a first signal source controlled by said first switch and a second signal source controlled by a second switch similar to said first switch including the additional step of operating said second switch between its open circuit condition and its closed circuit condition in opposition to said first switch.

14. A method of operating a switch having an open circuit

condition and a closed circuit condition from being predominately in a first one of said conditions to being predominately in a second one of said conditions comprising the steps of generating a repetitive waveform, generating a transition waveform which transitions between a minimum value which is less than the minimum value of the repetitive waveform and a maximum value which exceeds that of said repetitive waveform, comparing the instantaneous values of the two waveforms, operating said switch to said first condition when the instantaneous value of a first one of said waveforms exceeds that of said other waveform and operating said switch to said second condition when the instantaneous value of said first waveform is less than that of said other waveform.

15. The method of claim 14 adapted for switching between a plurality of signal sources controlled by switches similar to said switch including the steps of generating a transition waveform for each transfer between signal sources desired, selecting the pair of signal sources between which the transfer is to be made, operating a first switch controlling a first one of the selected signal sources to said first condition when the instantaneous value of the associated transition waveform exceeds that of said repetitive waveform, operating said first switch to said second condition when the instantaneous value of the associated transition waveform is less than that of the repetitive waveform and operating a second switch controlling the second one of the selected signal sources between its first and second conditions in opposition to said first switch.
